ATTORNEY.

UNITED STATES PATENT OFFICE.

EMILY T. KERVICK, OF BALTIMORE, MARYLAND.

PEW-GUARD.

SPECIFICATION forming part of Letters Patent No. 604,236, dated May 17, 1898.

Application filed November 17, 1897. Serial No. 658,781. (No model.)

To all whom it may concern:

Be it known that I, EMILY T. KERVICK, a citizen of the United States, residing at Baltimore, in the State of Maryland, have invented certain new and useful Improvements 5 in Pew-Guards, of which the following is a specification.

This invention relates to an improved lock and strap for church-pews.

10 The object of the invention is to provide an improved construction of pew lock and strap that may be used to guard the entrance of pews.

15 The invention is illustrated in the accompanying drawings, in which—

Figure 1 shows an elevation of two pews in section and the lock and strap in position. Fig. 2 shows the lock with the rear plate removed and exposing to view the internal construction. Fig. 3 is an edge view of the strap with the locking-prong in position ready to enter the lock-case. Fig. 4 is a view of the lock and strap with the locking-prong of the strap secured in the lock. Fig. 5 is a front 25 view of the lock. Fig. 6 is a side view of the bell-crank-shaped hook-catch. Fig. 7 shows three views of the locking-prong. Fig. 8 shows two views of the key.

The lock A is circular and is intended to be 30 secured to the end standard B of the pews on the inner side. As the lock-case has no angles or corners, there is no liability of a person's apparel or clothing catching on it. The case has a circular box-rim c and two flat 35 sides d d'. The rear side d' is a separate plate that sets within the circular rim. The two flat sides each have a central hole e and bolt-holes f, and the circular rim has an opening g. Within the case is a bell-crank-shaped hook- 40 catch, which has at its center and at each side a trunnion h, that fits and turns in the central hole e in the sides of the case. The exposed ends of the trunnions have a square hole i for the reception of the end i' of a key J. 45 One arm of the bell-crank has a hook-catch k, provided with a beveled outer side l, which normally is in front of the opening g in the circular rim. The other arm has a pin m projecting on the side which confronts the 50 said hook-catch, and a spiral spring n has one end seated over this pin and the other end seated against a lug o, fixed on the inside of

the case. This spring is under compression and keeps the beveled side l of the hook-catch immediately in front of the opening g and 55 the point of the hook-catch in contact with the lug o, in which position the locking-prong p on the strap, when entering the said opening, may bear on the said beveled side and thereby partly turn the bell-crank to allow 60 the prong p to fully enter and engage the hook-catch k.

The hook-catch is pivoted by its trunnions h, which are exposed through the sides of the case, and the key J is applied directly to a 65 hole i in the trunnion. The case itself has no keyhole, and therefore nothing can be inserted into the lock-case that will interfere with the action of the working parts.

The prong p has a hole p', into which the 70 hook-catch k enters and locks the strap Q when the latter is stretched across between the two pews. The prong-piece has two jaws r, which when first made are spread apart V-shaped, as shown in Fig. 7. One jaw has 75 two teeth s, one near each corner, and the other jaw has one tooth s' in the center. The end t of the strap is entered or placed between the two jaws while they are spread apart and then the jaws are pressed or hammered together, so as to force their teeth s s' into the strap end t, and thereby the locking-prong is secured to the strap, no rivets being employed. The other end of the strap Q is secured in like manner to a joint-piece u, which is jointed 80 to an eye v on a plate v', which latter is secured by screws to the next pew in front. When the strap is not in use to lock the pew entrance, it will hang pendent from the eye v, the locking-prong p being downward. 90

To lock the strap, no key is required. To unlock it, the end i' of the key J must be inserted in the square hole i in the trunnion and then turned.

The lock-case has been especially constructed to adapt it for use on any church-pew—those whose entrance are at the right-hand of an aisle as well as those whose entrance are at the left-hand—without changing the relative positions of the keyhole and the side 100 opening g for the entrance of the locking-prong p. It has also been a desideratum to make a pew-guard that will be entirely independent of the guard for adjoining pews.

Having thus described my invention, what I claim is—

A lock for holding a pew-guard strap, comprising a lock-case having a central pivot-hole, *e*, in each of two opposite sides and an opening, *g*, in its rim; a bell-crank-shaped lever having trunnions that fit in said pivot-holes, said trunnions being exposed externally and having a keyhole, and one arm of said lever having a hook-catch, *k*; a spring

pressing on the other arm of said bell-crank lever; and a strap having at one end a locking-prong to engage with said hook-catch, as set forth.

In testimony whereof I affix my signature in the presence of two witnesses.

EMILY T. KERVICK.
